ABRAHAM RANKIN, OF NEW YORK, N. Y.

CUFF FOR SHIRTS AND THE LIKE

Application filed July 28, 1927. Serial No. 208,930.

The present invention relates to cuffs for men's shirts and the like with a duplex cuff comprising a single cuff and a French or folded cuff.

The object of the invention is to provide men's shirts with both styles of cuffs so that at the option of the wearer either the single or the folded cuff may be exposed to use, and during use of either of the cuffs the other cuff will be concealed. Another advantage of the invention resides in the fact that, although both styles of cuffs are attached to the shirt, the extreme edge of the cuff in use will be flat and devoid of uncomfortable wrinkles.

In the drawings Fig. 1 represents a plan view of a portion of a shirt sleeve with the cuffs opened out and lying flat; Fig. 2 is a view on the line 2—2 of Fig. 1; Fig. 3 is a plan view with the French cuff folded and covering the single cuff; Fig. 4 is a view on the line 4—4 of Fig. 3; Fig. 5 is a plan view of a portion of the shirt sleeve with the cuffs folded transversely and exposing the French cuff; Fig. 6 is the same representation as Fig. 1 with the sleeve and cuffs folded transversely; Fig. 7 is a plan view of a portion of the shirt sleeve showing the single cuff lying flat; Fig. 8 is a view on the line 8—8 of Fig. 7; Fig. 9 is a plan view of a portion of the shirt sleeve with the cuffs folded transversely and exposing the single cuff.

The sleeve 1 has sewn thereto the single cuff 2 and the folded or French cuff 3. A continuous piece of material 4 constitutes a part of the inner lining of the single cuff 2 and the outer surface of the French cuff when it is folded. The outer surface of the single cuff consists of a piece of fabric 5. The upper edges of the fabric 4 and 5 are turned inwardly between which the edge of the sleeve 1 is inserted and then these three portions are united by stitching 6. The inner surface of the French cuff 3 and a portion of the inner surface of the single cuff 2 are formed from a single piece of fabric 7 which is folded or turned at 8 to form the inner surface 9 of the single cuff. The lowermost edges of the fabric 4 and 7 are turned inwardly and united by stitching 10. The lowermost edge of the

fabric 5 and the upper edge of the fabric 7 are turned inwardly and united by stitching 11. The French cuff 3 when folded along the edge 12 covers the single cuff and conceals it from view. The fold line 12 of the French cuff will be formed along the lowermost edge 13 of the single cuff and the single cuff will thereby tend to give firmness to the French cuff without forming folds or irregularities therein.

When it is desired to expose the single cuff to use, the French cuff 3 is drawn inwardly against the inside of the sleeve as shown in Fig. 8 thereby exposing the single cuff. The position of the French cuff when the single cuff is in use is shown in Fig. 9. In order that the free side edges of the cuffs may be united a series of buttonholes are provided. For the purpose of uniting the French cuff when in use buttonholes 14, 16, 14a and 16a are provided which, when the French cuff is folded to the position in Fig. 3, will align so that a cuff link may be passed through the four buttonholes. When the single cuff is in use, the buttonholes 14 and 15 on one side of the cuff and the buttonholes 14a and 15a on the other side of the cuff may be aligned and a suitable cuff link passed therethrough. The edges of the single cuff may also be secured by means of a button 17 passed through the buttonholes 14a and 15a. The sleeve may be provided with a button 18 and a buttonhole 19 provided for the purpose of securing the French cuff inside of the shirt sleeve when the single cuff is in use. This may be done by passing the button 18 through the buttonholes 16, 16a and 19 as will be evident from an examination of Fig. 9.

It will be observed from the foregoing description that the cuff structure is composed essentially of three sections, the first section 2, constituting the outside portion of the single cuff, a second section 7 (see Fig. 2) and a third section 4. The sections 2, 4 and 7 have a width in a direction of the length of the sleeve 1 and a length transverse thereto. A portion of the section 7 (see Fig. 2) constitutes part of the single cuff as well as part of the French cuff. The section 4 is united at one of its edges with the section 7 and at its

opposite edge, with section 2, to the shirt sleeve 1. As shown in Fig. 8 the section 4 comprises two portions of unequal length, the shorter portion being continuously adjacent to section 2, while the longer portion is continuously adjacent to section 7. When the structure shown in Fig. 8 is folded into a French cuff, indicated in Fig. 4, the fold in the section 4 (shown in Fig. 8) disappears, while a new fold approximately midway of the section 4 becomes the frontmost edge of the French cuff. When the cuff is folded into a French cuff the buttonholes 14 and 16 mate and buttonholes 14a and 16a mate. When the cuff is folded into a single cuff then the buttonholes 14 and 15 mate and the buttonholes 14a and 15a mate. A third set of single buttonholes 16 and 16a align with the buttonholes 14 and 14a when the cuff becomes a French cuff. The result of this arrangement is that whether the cuff is used as a single or French cuff, the cuff button, whether a link or a stud, when inserted through mating buttonholes will, in each case, pass through four and only four aligned buttonholes.

Of course, in speaking of the component parts of the cuff structure as fabric sections, it is not necessary that the sections be made of separate pieces of fabric or of pieces of fabric independent of the other sections.

Various changes in the specific form shown and described may be made within the scope of the claim without departing from the spirit of the invention.

What I claim is:

A duplex cuff structure for shirts and the like adapted to be used alternately as a single cuff or as a French cuff, said structure comprising a fabric section constituting the outside portion of the single cuff, a second fabric section constituting part of the inner portion of the single cuff as well as the inner portion of the French cuff, said first section being associated along one of its edges with said second section, a third fabric section being associated at one of its edges with the second section and of approximately equal length thereto, said third section being associated along its opposite edge with the shirt sleeve, a single buttonhole common to the first named section and the third section at each of the lateral extremities of said sections near the free edge of the French cuff, a single buttonhole common to the second section and the third section at each of the lateral extremities of said sections near the free edge of the French cuff, a single buttonhole common to the second and the third sections at each of the lateral extremities of said sections, said last named buttonhole and said first named buttonholes being adapted to be aligned when the structure is in the condition of a single cuff and whereby, the cuff may be converted either to a single cuff or a

French cuff and the buttonholes may be mated for the insertion of a cuff button passing, in each case, through four and only four mating buttonholes.

In testimony whereof I have hereunto set my hand.

ABRAHAM RANKIN.
